Des. 216,203
Patented Dec. 2, 1969

216,203

COMBINED DESK AND FILE RACK UNIT

Elmer J. Hess, Hopkins, Minn., assignor to Kwik-File,
Inc., Minneapolis, Minn., a corporation of Minnesota

Filed Oct. 16, 1968, Ser. No. 14,006

Term of patent 14 years

Int. Cl. D6—01

U.S. Cl. D33—7

FIG 1

FIG 2

FIG 3

FIG 4

FIG 5

FIG 6

FIG. 1 is a rear perspective view of one embodiment of a desk embodying my novel design,

FIG. 2 is a front perspective view thereof,

FIG. 3 is a rear elevational view thereof,

FIG. 4 is a front elevational view thereof,

FIG. 5 is a top plan view thereof, and

FIG. 6 is a side elevational view thereof, the other side thereof being identical,

The essential features of my design reside in those portions shown in full lines on the drawings.

I claim:

The ornamental design for a combined desk and file rack unit, as shown and described.
